New York

Filed Mar. 6, 1962, Ser. No. 69,109

Term of patent 14 years

(Cl. D34—15)

FIG. 1

FIG. 3

FIG. 2

FIG. 4

FIG. 5

FIG. 1 is a perspective view of a gyroscope toy showing my design;

FIG. 2 is a view looking toward one face of the toy;

FIG. 3 is an edge view of the same, looking toward the right of FIG. 2;

FIG. 4 is a view looking toward the opposite face of the toy; and

FIG. 5 is an edge view of the same, looking toward the bottom of FIG. 2.

The dominant feature of my design resides in the portions shown in full lines, the broken lines being shown only in FIG. 1 for convenience of illustration.

I claim:

The ornamental design for a gyroscope toy, substantially as shown and described.
